UNITED STATES PATENT OFFICE.

HENRY HERMAN MEYER, OF RED WING, MINNESOTA.

AIR-SUCTION REGULATOR.

1,344,921.

Specification of Letters Patent. Patented June 29, 1920.

Application filed February 28, 1919. Serial No. 279,849.

To all whom it may concern:

Be it known that I, HENRY H. MEYER, a citizen of the United States, residing at Red Wing, in the county of Goodhue and State 5 of Minnesota, have invented certain new and useful Improvements in Air-Suction Regulators; and I do hereby declare the following to be a full, clear, and exact description of the invention, such as will enable others 10 skilled in the art to which it appertains to make and use the same.

The present invention relates to a regulator or controller for regulating the air suction or sub-atmospheric pressure in a grain 15 separator or other contrivance, and aims to provide a novel and improved device of that character operable to automatically maintain a desired air suction or sub-atmospheric pressure, in order that the separation or 20 other operation being performed will be uniform even though the speed of the air suction fan may vary or other conditions tend to disturb the air suction, so that the present invention results in a steady air suction 25 under all conditions whereby the separation will be uniform.

A further object is the provision in a casing, from which air is drawn by an air suction fan, of air inlet means for relieving the 30 suction in the casing, and novel means for automatically controlling the air from the atmosphere through said air inlet means, whereby the inlet of air is controlled according to the suction, to provide for a constant 35 sub-atmospheric pressure in the casing.

It is also the object of the invention to provide a device of the nature indicated which is simple, compact and inexpensive in 40 construction, and which can be readily installed on various grain separators and the like.

With the foregoing and other objects in view as will be apparent as the description proceeds, the invention resides in the construction and arrangement of parts herein-after described and claimed, it being understood that changes can be made within the scope of what is claimed without departing from the spirit of the invention.

50 The invention is illustrated in the accompanying drawings, wherein:—

Figure 1 is a side elevation of a separator, showing the improvements applied thereto.

Fig. 2 is a plan view thereof.

55 Fig. 3 is a cross section on the line 3—3 of Fig. 1.

The regulator is illustrated as being applied to a grain separator, which comprises a casing 1 having a lower inclined screen 2 over which the grain passes, so that the air 60 suction will draw air upwardly through said screen for carrying with it the chaff, dust and lighter particles, as well known. Built in the casing 1 is an air suction fan comprising a housing 3 having the central side air 65 inlets 4 located within the casing 1, a fan 5 rotating within the casing for drawing air through the openings 4 from within the casing, and discharging the air, dust, and other foreign matter, through the outlet 6 and flue 70 (not shown) leading therefrom. The foregoing structure is typical, and is shown for the purpose of depicting the use of the regulator thereon.

In carrying out the invention, as shown, 75 the top of the casing 1 is provided at opposite sides of the fan housing 3 with air inlet openings 7, and valves or doors 8 are hinged to the top of the casing to close said openings, and to swing downwardly for the purpose of admitting air from above to the opposite sides of the housing 3 and air inlet openings 4 thereof. The valves 8 have up-standing segments 9 which serve as weights for swinging the doors open downwardly. 85

In order to control the valves 8 so that they will automatically open and close as the air suction increases and decreases, respectively, there is provided a lever 10, which, as shown, is of U-shape to extend partially around the housing 3. The lever 10 is fulcrumed, as at 11, on the casing 1, and the terminals of the lever are connected by straps 12 to the valves 8 to bear against the curved surfaces of the segments 9, so that 95 the rocking movement of the lever will raise and lower said valves for controlling the inflow of air. The cross piece or yoke of the lever is provided with an upstanding pin 13 for receiving apertured weights 14 100 to counterbalance the valves 8. The weights 14 thus tend to raise the valves 8 and close them with the desired tension or pressure against the air suction from within the casing. 105

In operation, a sufficient number of weights 14 are used to regulate the air suction as desired, so that the sub-atmospheric pressure in the casing 1 will remain steady, even though the fan 5 should rotate faster 110 or slower at times. Thus, if there is an increase of the air suction, due to the speeding

of the fan, this will act against the valves 8 and swing them downwardly, thus letting in more air through the openings 7 and offsetting the increase of air suction, in order 5 that the suction through the screen 2 will remain the same. The valves 8 are normally slightly open, so as to admit air through the openings 7 during the normal speed of the fan, the air suction swinging said valves 8 10 downwardly for the purpose, and it will therefore be obvious, that should the fan 5 slow down the air suction against the valves 8 will be relieved accordingly, thus permitting the weights 14 to swing said valves 15 closed. This will shut off the flow of air through the openings 7, and thereby increase the suction through the screen 2, which if this did not occur, would be reduced. In this way, as the suction is increased and reduced within the casing 1, the valves 8 swing 20 open and close accordingly, and thus uniformly maintain the desired suction through the screen 2 even though there are varying degrees of suction created by the fan. By 25 having the fan housing 3 built within the casing 1, advantage is taken of the opposite air inlets 4 of the fan housing, whereby air is drawn from within the casing 1 through the opposite sides of the fan housing, thus providing for a greater flow of air, and a more uniform flow through the screen 2. In the use of the fan housing as shown 30 and described, the air inlet openings 7 and valves 8 at opposite sides of the housing 3 are important, whereby to admit air to both inlets 4, for otherwise there would be a variation in the flow of air at the opposite sides of the fan. Furthermore, with this arrangement, the openings 7 can be as close 35 as possible to the openings 4 of the fan housing, and with the use of two valves 8 at the opposite sides, such valves are each of smaller size than if a single valve were used, and the operation is made more efficient and 40 reliable with such valves operated simultaneously one with the other.

By adding more weight on the arm of the

lever 11, this will increase the normal suction through the screen, and by taking off some of the weights 14, this will decrease the 50 suction so that same can be regulated by simply providing the necessary weight on the free arm of the lever 10.

Having thus described the invention, what is claimed as new is:—

55

1. The combination of a casing having a screen for the passage of air, means connected to the casing for sucking the air therefrom, said casing having air inlets at opposite sides of said means, valves for said 60 inlets arranged to open inwardly as the suction increases, a U-shaped lever extending partially around said means and fulcrumed between its terminals and intermediate portion on the casing at opposite sides of said 65 means, the terminals of the lever being connected to said valves, and means for swinging the intermediate portion of said lever to move the valves outwardly and adapted 70 to regulate the tendency for closing said valves.

2. The combination of an air suction casing having a screen for the passage of air into the casing, a fan housing built in the 75 casing for sucking air therefrom, the casing having air inlet openings at opposite sides of the fan housing for relieving the air suction, of valves for said openings arranged to open inwardly as the suction increases, and a U-shaped lever fulcrumed to 80 the casing and extending partially around the fan housing, the terminals of said lever being connected to the valves, and the lever having means at the yoke portion for receiving weights to regulate the opening of 85 the valves.

In testimony whereof I have signed my name to this specification in the presence of two subscribing witnesses.

HENRY HERMAN MEYER.
